FRANK A. LUNDQUIST, OF CHICAGO, ILLINOIS, ASSIGNOR, BY MESNE ASSIGNMENTS,
TO HENRY S. CONRAD, TRUSTEE.

LINE SWITCH AND CONNECTIONS.

Application filed October 23, 1918. Serial No. 259,398.

To all whom it may concern:

Be it known that I, FRANK A. LUNDQUIST, a citizen of the United States of America, and a resident of Chicago, county of Cook, 5 and State of Illinois, have invented certain new and useful Improvements in Line Switches and Connections, of which the following is a specification.

My invention relates to line switches and 10 their connections in automatic telephone exchanges, and has for its object improvements in such devices. One object which may be mentioned as a preliminary is an arrangement by which I dispense with the third 15 wire normally used between the connector and the subscriber's switch. Another object which I will mention in my preliminary statement is an arrangement by which I use the test magnet as a line relay.

20 The accompanying drawing is a diagram of a line switch and the connections leading to and from the switch as far as such connections are necessary to an understanding of the present invention.

25 In the center of the drawing is a tube 1 which slides on a standard 2 when compressed air is admitted from pipe 3 to the interior of standard 2. These parts constitute a pneumatic motor which will be referred to as motor 1. On the top of motor 1 are some insulated wipers which are designed to make electrical connections with stationary contacts when the motor 1 is operated.

35 On one side of motor 1 are ratchet teeth 4 adapted to be engaged by a pawl 5 to stop the motor at any desired position. A magnet having coils 6 and 7 acts upon its armature 8 to move pawl 5 into engagement with 40 teeth 4. A spring 9 acts to move pawl 5 away from teeth 4 and to move armature 8 to its retracted position.

45 Adjacent to the magnet 6-7 is a valve 10 to which compressed air flows from a local supply pipe 11. The valve 10 is in the nature of a check valve which is normally held closed by the pressure of air in pipe 11. It has a stem 12 which engages the armature 8 and acts to push said armature toward its 50 retracted position. Back of armature 8 is a spring 13 which acts to push the armature 8 toward its attracted position and to hold said armature in contact with stem 12. The combined force of spring 9 and the air 55 pressure on valve 10 is greater than the force

of the spring 13, so that armature 8 is normally held in its retracted position. But when the magnet is energized, the attraction on armature 8 plus the force of spring 13 is greater than the combined force of spring 9 60 plus the air pressure on valve 10, with the result that the valve is opened when the magnet is energized. When the valve 10 is opened, air flows from pipe 11 to pipe 14 and thence to a motor 15 which is of the 65 same character as motor 1. In normal position, valve 10 permits air to exhaust from pipe 14.

At a convenient place is a magnet composed of coils 16 and 17 and armature 18. 70 A spring 19 presses armature 18 against the stem of valve 20, but with a force less than enough to open said valve. But when the magnet 16-17 is energized, the valve 20 is opened to permit compressed air to flow 75 from pipe 11^a to pipe 3. The pipe 11^a is a branch of the supply pipe 11.

Pivoted at 21 to the frame of the switch is a bell crank lever 22, one arm of which rests on motor 15 so that when said motor is 80 operated said arm is lifted to shift adjacent contact springs. To the other arm of lever 22 is pivoted an arm 23 which is pulled upward by a spring 24. When motor 1 is in normal position, a pin 25 on said motor 85 engages the arm 23 to hold it in the position shown. If the motor 15 operates when the motor 1 is in normal position, then the movement of lever 22 pushes arm 23 so as to shift the adjacent contact springs to the 90 right. But if motor 15 operates after motor 1 has operated, then spring 24 has pulled arm 23 upward so that the said arm passes over the adjacent contact springs without touching them.

In addition to the parts so far described there are batteries X and X', a generator G, another motor and valve with levers and springs, certain contact springs, and wipers for engaging stationary contact points shown 100 in the upper part of the drawing. These will be fully understood from the description to follow.

From the line switch wires 30 and 31 extend to a local station to which the line 105 switch belongs. When the subscriber lifts his receiver from its hook he closes connection between these wires, whereupon a circuit is closed as follows: X-26-16-27-28-29-30-local station-31-32-33-34 110

17—X. When this occurs, the armature 18 is attracted to open valve 20 and permit compressed air to flow from the supply pipe 11^a to the pipe 3 and from thence to the motor 1.

When the motor 1 is operated as the result of such admission of air, it carries its wipers upward until they reach contact points which represent an idle selector, whereupon a circuit is completed thru such selector as follows: X'—35—6—36—37—38—39—40—the found idle selector—41—42—43—44—45—7—48—X'. An idle selector is one which has a bridge across the contacts touched by the bushes 40, 41, and when the selector is seized by the line switch the bridge is opened.

The consequent attraction of the armature 8 throws the pawl 5 into the ratchet 4 and stops the motor 1 with its wipers in engagement with the stationary contacts which represent the found selector. The armature 8 also opens valve 10 to admit air to motor 15, which motor tilts bell crank 22 to shift springs 37 and 44 from previous position to contact with springs 55 and 60. Motor 15 also tilts bell crank 49 to open valve 50 and permit compressed air to flow from pipe 3 thru pipe 51 to motor 52. This motor shifts springs 29 and 32 so as to break the circuit for magnet 16—17 and to connect the station wires 30 and 31 to the wipers 57 and 62 as follows: 30—29—53—54—37—55—56—57; and 31—32—58—59—44—60—61—62.

35 When motor 15 moves lever 49 as before described, such movement of 49 permits spring 63 to turn lever 64 on its pivot so that the catch 65 comes over the tail of armature 18. As this occurs at the time, or 40 slightly before, the circuit is broken thru magnet 16—17, the armature 18 is retained in its attracted position and the valve 20 is held open so that air remains on motors 1 and 52.

45 The parts remain in this condition while the subscriber at the local station reached by wires 30 and 31 is talking to a called subscriber. When the calling subscriber hangs up his receiver he breaks the circuit 50 for magnet 6—7 and this permits motor 15 to fall back. This in turn shuts air from valve 50 and permits motor 52 to fall back. The same movement which permits valve 50 to close also turns arm 64 to release catch 55 65 from armature 18 so that said armature returns to normal position. This lets valve 20 close, whereupon motor 1 falls back to normal position.

When 15 first operated as previously described it was after motor 1 had moved. Consequently, the tilting of bell crank 22 resulted in arm 23 passing over the adjacent contact springs and into a position which brought the hook 66 on arm 23 behind 65 a stationary block or catch 67. When mo-

tor 15 released as described, spring 37 acting on bell crank 22 can return only part way to normal position until the fall of motor 1 causes pin 25 to release hook 66 from catch 67. What happens is that springs 37 and 44 are suspended between the upper and lower contacts with which they normally engage but from which they are wholly disengaged during release operations.

From the line switch wires 68 and 69 lead 75 to contacts on connector switches, and when some other subscriber calls the subscriber associated with this line switch he closes extensions of lines 68 and 69 whereupon a circuit is completed as follows: X'—35—6—36—37—40—70—71—68—connections made by the calling subscriber—69—72—73—59—7—48—X'.

This actuates magnet 6—7 which throws pawl 5 into ratchet 4 so as to prevent motor 1 moving from normal position. The magnet also opens valve 10 so as to admit air to motor 15. This motor acts on bell crank 22 and causes arm 23 to push the adjacent springs into engagement with other contacts, 90 whereupon a current flows: generator G—74—75—76—77—78—29—30—local station—31—32—79—80—81—82—83—G.

This is a signalling circuit which calls the subscriber at the local station who removes his receiver and thereby closes a circuit thru the magnet 16—17 as in the previously described condition. The action of magnet 16—17 opens valve 20 and admits air to motor 1, and, thru previously opened valve 50, to motor 52. Owing to the fact that pawl 5 had been previously thrown into ratchet 4, motor 1 accomplishes nothing. But motor 52 shifts the adjacent contact springs to cut off generator G and connect 105 wires 30 and 31 to wires 68 and 69. These last may be traced as follows: 30—29—53—54—70—71—68; and 31—32—58—59—73—72—69.

From the description which applies to the 110 line switch as a calling switch it will be seen that the magnet 6—7 becomes a line relay which remains energized in a bridge across the talking circuit. When the line switch is a called switch, the magnet 6—7 115 is the test magnet which is energized over wires 68 and 69 leading back to a connector. If the line switch is already acting as a calling switch, then the rise of motor 1 lifts part 84 and the terminals of wires 68 and 69 are disconnected from spring 70 and 73 so that a calling subscriber cannot find a busy line switch. But instead the wires 68 and 69 are switched to a pair of springs 85 and 86 which connect to a common buzz circuit (not shown) whereby the calling subscriber secures a busy signal.

When motor 52 operated to cut off the generator G it also shifted the connections of wires 30 and 31 from the magnet 16—17 120

to the magnet 6-7 as described for the case in which the calling party is at the local station in wires 30-31. As the previous operation of motor 15 had tilted bell crank 5 49 and permitted 65 to catch on armature 18, the valve 20 is still held open and pressure is still on motor 1. But when the circuit is broken thru magnet 6-7, motor 15 will fall back and this turn will release armature 18 and permit valve 20 to close. The arrangement herein shown is such that the magnet 6-7 has its circuit closed thru both the calling and called station when the call comes from some station other than the one 15 associated with the line switch. As a consequence of this, the circuit for magnet 6-7 can be broken only when both subscribers hang up their receivers at the end of a conversation. No special appliances or attachments 20 are needed for preventing the line switch from making a trunk hunting movement when the called subscriber is the last to hang up.

What I claim is:

25 1. In a line switch and connections therefor, a magnet serving as a line relay when the switch is a calling switch, and as a ringing relay when the switch is a called switch.

30 2. In a line switch and connections therefor, a magnet serving at one time as a line relay and at another time as a magnet for holding the line switch at normal position, a signaling generator, means controlled by the magnet for connecting the generator to

35 the connections leading from the line switch to the local station associated therewith, and means by which such connections for the generator is interrupted when said magnet acts as a line relay.

40 3. A line switch having a pair of wires leading to a connector switch and a second pair of wires leading to a local station, a signaling generator, means controlled over the first pair of wires for connecting the generator to the second pair, and means for subsequently connecting the two pairs of wires to form a talking circuit.

45 4. A line switch having a pair of wires leading to a connector switch and a second pair of wires leading to a local station, a signaling generator, a pneumatic device for connecting the generator to the second pair of wires so as to call the subscriber at the local station, a magnet for controlling the operation of the pneumatic device, means for controlling the magnet by an impulse flowing over the first pair of wires, and means by which the wires carrying such impulse are subsequently used in a talking circuit to the local station.

50 5. In a line switch and connections therefor, a line relay by which the line switch is controlled, and connections so arranged that upon a call coming from a distant station to the station associated with the line

switch said relay will have its circuit closed thru both the calling and the called stations.

6. A line switch having a pair of wires leading to a connector switch and a second pair of wires leading to a local station, a magnet arranged to have its circuit closed thru the first pair of wires, and a pneumatic device controlled by said magnet for connecting the two pairs of wires to form a talking circuit.

7. A line switch having a pair of wires leading to a connector switch and a second pair of wires leading to a local station, a magnet bridged upon the talking circuit formed by connecting the two pairs of wires together, and a pneumatic device controlled by said magnet for controlling the completion of the circuit upon which it is bridged.

8. In a line switch and connections therefor, a magnet serving first as a test magnet and then as a line relay when the switch is a calling switch, and first as a ringing relay and then as a line relay when the switch is a called switch.

9. A line switch having a pair of wires leading to a connector switch and a second pair of wires leading to a local station, a signalling generator, means controlled over the first pair of wires for connecting the generator to the second pair, and means for subsequently disconnecting said generators from said second pair of wires and for subsequently connecting the two pairs of wires to form a talking circuit.

10. A line switch having a pair of wires leading to a connector switch and a second pair of wires leading to a local station, a signalling generator means controlled over said first pair of wires for connecting said generator to said second pair of wires to signal the subscriber at said local station, and a pneumatic device for subsequently connecting the two pairs of wires to form a talking circuit.

11. A line switch having a pair of wires leading to a connector switch and a second pair of wires leading to a local station, a magnet on said line switch having two windings, one of said windings normally connected to one of said first pair of wires and to one pole of battery, the other winding normally connected to the other wire of said first pair of wires and to the other pole of battery, means for operating said magnet over said first pair of wires, and means for connecting said magnet to said second pair of wires.

12. A line switch having a pair of wires leading to a connector switch and a second pair of wires leading to a local station, a magnet normally connected to said first pair of wires, a relay normally connected to said second pair of wires, means operated in response to the operation of said magnet when said switch is a calling switch for discon-

necting said relay from said second pair of wires, and said means operated in response to the operation of said relay when said switch is a called switch for disconnecting said relay from said second pair of wires.

13. A line switch having a pair of wires leading to a connector switch and a second pair of wires leading to a local station, a magnet normally connected to said first pair of wires, a relay normally connected to said second pair of wires, means operated in response to the operation of said magnet when said switch is a calling switch for disconnecting said relay from said second pair of wires and for connecting said magnet thereto, and said means operating in response to the operation of said relay when said switch is a called switch for disconnecting said relay from said second pair of wires and for connecting said magnet thereto.

14. A line switch having a pair of wires leading to a connector switch and a second pair of wires leading to a local station, a magnet normally connected to said first pair of wires, a relay normally connected to said second pair of wires, a pneumatic device operated in response to the operation of said magnet when said switch is a calling switch for disconnecting said relay from said second pair of wires, and said device operated in response to the operation of said relay when said switch is a called switch for disconnecting said relay from said second pair of wires.

15. A line switch having a pair of wires leading to a connector switch and a second pair of wires leading to a local station, a magnet normally connected to said first pair of wires, a relay normally connected to said second pair of wires, a pneumatic device in said switch for disconnecting said relay from said second pair of wires and for connecting both said pairs of wires together so that said magnet is connected to both of said pairs, said device operated in response to the operation of said magnet when said switch is a calling switch, and said device operated in response to the operation of said relay when said switch is a called switch.

16. A line switch having a pair of wires leading to a connector switch and a second pair of wires leading to a local station, a magnet normally connected to said first pair of wires, a relay normally connected to said second pair of wires, a device in said switch for disconnecting said relay from said second pair of wires and for connecting both said pairs of wires together so that said magnet is connected to both of said pairs,

said device operated in response to the operation of said magnet when said switch is a calling switch, and said device operated in response to the operation of said relay when said switch is a called switch.

17. In a line switch a pneumatic device on said switch for disconnecting generator from the called line and for connecting the calling and called lines together to form a talking circuit, a magnet and a relay on said switch, a source of air pressure, said relay partially completing an air passage from said source to said device and said magnet completing the air passage so as to cause the operation of said device when said switch is a calling switch, said magnet partially completing an air passage from said source to said device and said relay completing the air passage so as to cause the operation of said device when said switch is a called switch.

18. In a line switch, a pneumatic device on said switch for disconnecting generator from the called line and for connecting the calling and called lines together to form a talking circuit, a magnet and a relay on said switch, a source of air pressure, said relay partially completing an air passage from said source to said device and said magnet completing the air passage so as to cause the operation of said device when said switch is a calling switch, said magnet partially completing an air passage from said source to said device and said relay completing the air passage so as to cause the operation of said device when said switch is a called switch, and means controlled by said magnet for maintaining said device in operated position.

19. In a line switch, a pneumatic device on said switch for disconnecting generator from the called line and for connecting the calling and called lines together to form a talking circuit, a magnet and a relay on said switch, a source of air pressure, said relay partially completing an air passage from said source to said device and said magnet completing the air passage so as to cause the operation of said device when said switch is a calling switch, said magnet partially completing an air passage from said source to said device and said relay completing the air passage so as to cause the operation of said device when said switch is a called switch, and means by which either the calling or called line controls the release of said magnet to cause the release of said device.

FRANK A. LUNDQUIST.
